(57) **CLAIM**

The ornamental design for a compact disc container, as shown and described.

DESCRIPTION

FIG. 1 is a top plan view of the compact disc container of the present invention;

FIG. 2 is a bottom plan view of the compact disc container of FIG. 1;

FIG. 3 is a right side elevational view of the compact disc container of FIG. 1;

FIG. 4 is a left side elevational view of the compact disc container of FIG. 1;

FIG. 5 is a front elevational view of the compact disc container of FIG. 1;

FIG. 6 is a rear elevational view of the compact disc container of FIG. 1;

FIG. 7 is a top plan view of the compact disc container of FIG. 1 in an alternate position;

FIG. 8 is a top, rear, left side perspective view of the compact disc container of FIG. 7; and,

FIG. 9 is a bottom, rear, left side perspective view of the compact disc container of FIG. 7.

The broken lines showing of a compact disc in FIGS. 7 and 8 are for illustrative purposes only and form no part of the claimed design.
